UNITED STATES PATENT OFFICE.

HENRY HORAN, OF EAST ORANGE, NEW JERSEY, ASSIGNOR TO HARTFORD CARPET COMPANY, OF HARTFORD, CONNECTICUT.

DESIGN FOR CARPET.

SPECIFICATION forming part of Design No. 11,840, dated July 6, 1880.

Application filed February 12, 1880. Term of patent 3½ years.

To all whom it may concern:

Be it known that I, HENRY HORAN, of East Orange, in the county of Essex and State of New Jersey, have invented a new and original 5 Design for Carpet, of which the following is a specification.

This invention relates to a new and original design for carpets, oil-cloths, and similar fabrics.

10 It consists in the novel grouping and configuration of figures, hereinafter more fully described and claimed.

The accompanying photograph illustrates a face view of a carpet having my new design.

15 On the background A of the carpet is a wreath, B, composed of flowers and leaves, and in the center of the wreath is a bunch of flowers and leaves, a. Below the wreath is an ornamental wall, C, partially inclosing the 20 wreath, over which wall some of the flowers and leaves from the wreath droop.

D is a small bunch of flowers and leaves. E is a fret-work fence resting in and partially covered by leaves and flowers b. Above the 25 fence is a large and brilliant group, E', composed of flowers F and gracefully-drooped leaves d. Part of the said leaves droop over the fence E. The group E' is partly inclosed or surrounded by a zigzag wall, G, over which 30 leaves from the group are drooped.

An obliquely-placed rail, e, connects the fence E with a group, H, of flowers and leaves. Over the background A are scattered, at intervals between the larger groups, small groups 35 I of flowers and leaves.

I claim—

2. The design for a carpet, consisting of the 40 wall C, substantially as shown.
